UNITED STATES PATENT OFFICE.

MARION S. HOLLEY, OF ENTERPRISE, KANSAS.

SELF-LOCKING CHICKEN COOP.

Application filed July 18, 1925. Serial No. 44,574.

The invention relates to chicken coops for feeding and shipping poultry and has for its principal object the provision of improved means for securing the sliding door for access to the coop, said securing means being automatic in operation.

Another object of the invention is an improved construction of the coop in itself by which a thoroughly ventilated and sanitary 10 coop is provided at a minimum cost of production and that is so constructed that all danger of spreading of the wire panels forming the sides of the coop is avoided and escape of the fowls therefrom obviated.

15 The construction and operation as well as the advantages of the invention will be described in detail hereinafter and the construction will be found illustrated in the accompanying drawings in which

20 Figure 1 is a top plan view of the improved chicken coop,

Figure 2 an end view,

Figure 3 a transverse sectional view on a plane indicated by the line 3—3 of Figure 1,

Figure 4 a sectional detail on a plane indicated by the line 4—4 of Figure 1,

Figure 5 a sectional detail on a plane indicated by the line 5—5 of Figure 4,

30 Figure 6 a section on the plane indicated by the line 6—6 of Figure 5,

Figure 7 a fragmental view showing a modification of the structure of the loop for the sliding arm, and

35 Figure 8 a transverse section on a plane indicated by the line 8—8 of Figure 7.

In the drawings similar reference characters will be used to designate corresponding parts throughout the several views.

40 The improved chicken coop has a floor 1 along the edges of which are secured upright sills 2, corner posts 3 secured to the floor 1 and sills 2 and head beams 4 connecting the upper ends of the corner posts 3.

45 In the coop selected for illustration two compartments are provided and said compartments are formed by means of a transverse partition comprising end posts 5 and foot and head pieces 6 and 7 respectively. It

50 will be understood, however, that more than one partition may be provided to form the coop into three or more compartments if desired.

55 In each of the frames formed by end posts 3, and sills 2 and 4, and also in the frame formed by end posts 5 and foot and head

pieces 6 and 7, a panel of wire fabric is provided, said panel in each instance comprising longitudinal wires 8 and vertical wires 9 that are welded at the intersection of said wires to prevent spreading of the wires. Each panel comprising the wires 8 and 9 is secured in its respective frame by means of suitable driven fastenings such for instance as staples 10.

60 The top of the coop is provided with longitudinal panels of large mesh woven wire screen designated 11 secured to longitudinal strips 12, and said strips are secured to the head beams 4 and 7. The panels comprising the wire screen 11 and strips 12 are spaced apart to form an elongated opening therebetween through which the contents of the coop may be removed and replaced, and said opening is closed by means of a door 13. 65 The door 13 is slidably mounted between guides formed by elongations of vertical wires 9 of the end and partition panels, and a cross wire 15 welded adjacent its ends to said elongated wires 9.

70 In order to lock the sliding door 13 to prevent accidental removal thereof, an opening 15 is provided therein intermediate of its ends, and a spring actuated bolt is provided therefor. The bolt is designated 16 and is 75 slidably mounted in a tubular member 17, said tubular member having an inset flange 18 at its lower end on which is seated an expandable coil spring 19 that also engages a shoulder 20 on the bolt 16 and holds said 80 bolt normally protracted into a locking position in the opening 15. Said tubular casing 17 has its upper end curved outwardly as shown at 21 to form a recess flange that engages the upper edge of a housing 22 that is 85 secured to a baton 23 that is in turn secured to the foot and head beams 6 and 7.

90 The operation of the sliding door will be clearly understood from the drawing, the only thing necessary to secure access to the 100 coop being to retract the sliding bolt 16 below the lower edge of the sliding door 13 and then by moving the sliding door in either direction access may be had to the compartment of the coop desired, and when the sliding door is returned to its original position, the bolt 16 automatically returns to its position in the opening 15 and holds the door 105 from movement in either direction.

110 In Figures 7 and 8 are shown a modified structure of loop for the sliding door comprising vertical wires 24 bent at right angles

under the head beam or piece 25 as shown at 24^a and then upwardly on the opposite side of said head beam or piece from the vertical portions 24, as shown at 24^b, 26 indicating staples or other suitable fastenings to secure the parts 24, 24^a and 24^b to said head beam or piece 25. 27 indicates cross wires welded to the vertical portions 24.

What is claimed is:—

- 10 In a chicken coop, a container having an opening in its top extending from end to end thereof, a door slideable in said opening and having an opening therethrough, a parti-

tion intermediate of the ends of the container, a housing secured to said partition, 15 and a spring actuated bolt in said housing adapted to engage in said opening when the door is in closed position to prevent casual displacement thereof, retraction of said bolt being effected through the opening from the 20 outer side of the door and permitting the door to slide on the container without lifting.

In testimony whereof I affix my signature.

MARION S. HOLLEY.
